UNITED STATES PATENT OFFICE.

GEORGE C. D. MILLER, OF NEW YORK, N. Y., ASSIGNOR TO CARY MANUFACTURING COMPANY, OF NEW YORK, N. Y., A CORPORATION OF NEW YORK.

WIRE BOX-STRAPPING.

1,099,189.

Specification of Letters Patent.

Patented June 9, 1914.

Application filed July 13, 1912. Serial No. 709,125.

To all whom it may concern:

Be it known that I, GEORGE C. D. MILLER, a citizen of the United States, residing in the city of New York, borough of Brooklyn, county of Kings, and State of New York, have invented a certain new and useful Wire Box-Strapping, of which the following is a specification.

This invention is a wire strap for use in 10 nailing shipping boxes and crates.

Prior to my invention, box strapping had been manufactured from sheet metal and twisted wire. The wire strap has been composed of two wires twisted together throughout the length thereof except at certain predetermined intervals, at which intervals the two wires have been bent to produce eyes through which nails are driven to fasten the strap upon the box or crate. The strap 15 produced in the usual way consumes more wire than it should in proportion to the length of the resulting strapping, due to the twisting of the wires together. Furthermore, with the eyes at predetermined 20 intervals it is not possible in many instances to drive the nails in the proper places. Again, the strapping as usually made is provided with eyes at two inches apart, at 25 four inches apart, or at six inch intervals, and when such strapping is bent around the corner of a box or case, the eyes in the strapping are not positioned for the 30 advantageous driving of the nails.

The object of this invention is to overcome 35 the foregoing and other objections inherent in the manufacture and use of wire strapping.

The strap of the present invention is capable of manufacture economically for the 40 reason that it requires considerably less material, whereby a saving of ten per cent. (10%) in the quantity of material is effected. The strap embodies a plurality of wires preferably two in number, which are 45 twisted together at intervals, the wires between the twists being parallel or untwisted, thus resulting in a new article characterized by an absence of spaced eyes or loops. The wires at the twisted portions thereof are 50 twisted together two or more times and twisted tightly together, so that at said twisted parts the wires cannot become separated when the parallel portions intermediate the twists are spread laterally by driving 55 nails between said parallel portions.

Furthermore, it is preferred to twist the wires at one point toward the right and at the two adjacent points toward the left, so that the adjacent twists are of reverse hand; and it is preferred, also, to position the parallel strands intermediate the twists in close relation to, or in actual contact with, each other. By eliminating the twists throughout the length of the strap, a considerable saving in wire is effected. The strap is 60 nailed in position by driving the nails between the parallel strands and preferably next to the twisted portions in such manner that the strap is drawn taut around the shipping case or box.

In the accompanying drawings, I have 65 illustrated one practical embodiment of the invention, but the construction shown therein is to be understood as illustrative, only, and not as defining the limits of the invention.

Figure 1 is a perspective view of a part 70 of a box corner with the wire strap nailed thereto. Figs. 2 and 3 are views in plan and elevation, respectively, on an enlarged scale. Fig. 4 is a cross section through the strap 75 on the line 4—4 of Fig. 3, showing a part of a box and a nail.

The strap is composed of a plurality of 80 wires, preferably two in number, indicated at A, B, each wire being of suitable size and strength. The wires are twisted together at intervals, as at b, c, and intermediate these twists the wires are positioned parallel to each other to produce parallel strands d, d', 85 e, e', f, f'. As shown, the parallel strands are in contact with each other, there being no appreciable space or interval between them. The wires are, preferably, twisted tightly together at b, c, and the adjacent 90 twists extend in opposite directions, thus twist b is of the opposite hand or direction to alternate twists a, c, twist b being right handed and twists a, c being left handed.

The strap is passed around the corners of 95 a box or case C, and as usual it is fastened in place by first driving a nail into the box, after which the strap is pulled by hand to keep it tight. When bending the strap around the next corner of the box, one or 100 more nails, as D, are driven into the box in a manner to stretch the strap from the point at which it is fastened initially. Each nail is driven between the strands, and preferably 105 next to a twisted portion of the strap, 110

the tendency of which is to slightly spread the strands at the location of the nail and to thus draw upon the strap for tightening it to a certain extent. The nail is driven 5 through the parallel strands and quite close to the twist, the latter affording a point of bearing or contact for the nail with the strap. By inclining the nail or nails, and driving the nails in inclined directions be- 10 tween the parallel strands and next to the twists, the operation of the nails on the strap tends to pull on and tighten said strap, thereby applying and securing the strap in the most advantageous manner.

15. It will be noted that the new strap is free from the usual nail-receiving eyes, and, accordingly, that it is not open to the practical objection so frequently made by persons in applying the strap to a box or case, to wit, 20 that the nails cannot be driven except at predetermined points. Manifestly, the nails can be driven through the new strap at practically any point, except through the twists, but it is preferable to drive the nails quite 25 close to the twisted parts of the strap in order to pull upon and stretch the strap.

Having thus fully described the invention, what I claim as new, and desire to secure by Letters Patent is:—

30. 1. An eyeless box strap comprising a plurality of wires twisted tightly together at predetermined intervals, the lengths of the wires intermediate the twisted parts of the strap being parallel for the purpose of receiving nails which operate to spread said 35 parallel lengths laterally with respect to each other, whereby, upon fastening the strap to a package by driving initial securing nails at predetermined points 40 through said strap, the operative length of the strap is so reduced between said initial securing nails as to substantially tighten the strap upon the box to which it is applied.

2. An eyeless box strap comprising a pair of wires twisted tightly together at regular 45 intervals, the wires between such twisted portions being parallel and in substantial contact with each other, whereby the parallel portions of the wires are adapted to be spread laterally by driving nails between 50 them and the strap is tightened upon a box to which it is applied by a substantial decrease in the operative length of the strap due to such lateral spreading of the parallel wires.

55. 3. A box strap comprising a pair of wires twisted together tightly at predetermined intervals in the length thereof, the adjacent twists being in opposite directions and the wires intermediate the twisted portions being parallel to each other, the space between such parallel wires being less than the thickness of the nails adapted to be driven between them, whereby said parallel wires are adapted to be spread laterally for the purpose of drawing the strap taut upon a box to which it is applied.

60. 4. A box strap comprising a pair of parallel wires twisted tightly together at predetermined intervals, said wires being 70 parallel and in lateral contact with each other in the intervals between said tightly twisted portions, said contacting and parallel portions of the wires being adapted to be spread laterally by driving nails between 75 them, whereby the strap is tightened upon the box or other device to which it is applied.

80. In testimony whereof I have signed my name to this specification in the presence of two subscribing witnesses.

GEORGE C. D. MILLER.
